WATER SKI VEST

Leonard P. Frieder, Jr., Waverly, Pa., assignor to Gentex
Corporation, New York, N.Y.

Filed June 9, 1971, Ser. No. 151,617

Term of patent 14 years

Int. Cl. D2—02

U.S. Cl. D71—1 HH

FIG. 1

FIG. 3

FIG. 1 is a front elevation of a water ski vest showing my new design.

FIG. 2 is a right side elevation thereof, the other side being substantially a mirror image.

FIG. 3 is a rear elevation thereof.

I claim:

The design for a water ski vest, substantially as shown and described.
